UNITED STATES PATENT OFFICE.

LILLIAN C. NESBITT, OF LAS CRUCES, NEW MEXICO.

INSECT SCREEN FOR BEDS.

Application filed April 25, 1924. Serial No. 708,947.

To all whom it may concern:

Be it known that I, LILLIAN C. NESBITT, a citizen of the United States, residing at Las Cruces, in the county of Dona Ana and 5 State of New Mexico, have invented certain new and useful Improvements in Insect Screens for Beds, of which the following is a specification.

My invention relates to a screen especially 10 designed to afford a protection against insects of all kinds, particularly flies and mosquitoes.

One object of the invention is to provide 15 a protector of this kind for beds or cots, and another object is to construct the protector in such a manner that it may be folded to take up very little space, thus making it suitable for tourists or camping parties.

20 The protector consists of a stand preferably made from wire having side frames hinged to the back frame thereof. This stand is intended to be placed over the top of a bed or cot and secured thereon. A hood 25 of mosquito netting fits over the stand and terminates in a wide skirt at its bottom edge which may be tucked under the bed clothes.

In the accompanying drawings, one embodiment of the invention is illustrated, and 30 Figure 1 is a perspective view of the protector as erected over the head of a bed or cot;

Figure 2 is a fragmentary section along line 2—2 of Figure 1, and

35 Figure 3 shows the stand in folded position.

In the drawing, reference numeral 10 represents a bed having side rails 11. Upon these side rails is erected an upright frame 40 or stand 12. This stand comprises a back frame 13 preferably made of wire. This frame is of rectangular outline and to the same is hinged a triangular side frame 14 on each side thereof. Each side frame is also 45 preferably made of a piece of wire, the ends of which are looped, as at 15, to encircle the uprights 16 of the back frame 13, one at the top and one at the bottom thereof. The bottom rod 17 of each triangular side frame 50 runs at right angles to the upright 16, while the upper rod 24 thereof slopes downwardly from the hinge 15 to the blunt point 18 of the frame. The length of each side frame is preferably such that it may be folded down 55 between the uprights 16 of the back frame 13, as best seen in Figure 3.

Upon the bottom rods 17 of the side frames are hooks 19 near the ends thereof, which hooks are adapted to engage under the side rails 11 of the bed, as indicated 60 in Figure 1. A strap 20 is adapted to connect the two forward ends 18 of the side frames and this strap is provided with a buckle 21 or other securing device.

When erected as indicated in Figure 1, the 65 back frame 13 is set up at the rear of the bed so that the stand slopes forwardly as clearly shown.

Over the stand is fitted a hood or canopy 70 22 made of mosquito netting or similar fabric. This hood is stretched over the back and side frames and covers the top formed between the upper rods 24 of the side frames. The hood terminates at its bottom in a skirt 75 23 which preferably extends around all sides thereof and this skirt is intended to be tucked under the bed clothes.

During transportation the frame is folded as seen in Figure 3, and the hood preferably detached therefrom. The forward 80 part of the hood fits loosely over the stand so that it may be pushed up completely or partly along the upper rods 24 of the side frames.

In order to erect the protector on a bed, 85 the back frame 13 is first placed across the bed in upright position and the side frames swung in so that the hooks may engage under the rails 11 of the bed. As soon as the back and side frames are in position the strap 20 is drawn under the bedding and its ends secured together by means of the clasp or buckle 21. Lastly, the hood is thrown over the stand and the protector is 90 ready for use.

Having thus described the invention, what 95 is claimed as new is:

1. A protecting screen for beds comprising an upright back frame, substantially 100 triangular side frames pivotally connected with the back frame and movable laterally to folded position against the back frame, a canopy fitted over said frames, an adjustable connection between the reduced ends of the side frames, and means for supporting 105 said frames in position on a bed.

2. A protecting screen for beds comprising an upright back frame, substantially 110 triangular side frames pivotally connected with the back frame and movable laterally to folded position against the back frame, a canopy fitted over said frames, and means

depending from the side frames for engagement with the side rails of the bed.

3. A protecting screen for beds comprising an upright back frame, substantially triangular side frames pivotally connected with the back frame and adapted to be swung inwardly to folded position against the back frame, a canopy fitted over said frames, and hooks depending from the side frames for engagement with the side rails of a bed.

4. A protecting screen for beds comprising an upright back frame, substantially triangular side frames pivotally connected with the back frame and adapted to be swung inwardly to folded position against the back frame, a canopy fitted over said frames, an adjustable strap connecting the reduced ends of the side frames and adapt-

ed to extend transversely across the bed, and fastening devices depending from the side frames for engagement with the side rails of said bed.

5. A protecting screen for beds comprising a hollow substantially rectangular upright back frame, hollow, substantially triangular side frames having terminal eyes fitting around the uprights of the back frame and pivotally connected therewith, the free ends of the side frames being blunt, an adjustable strap connecting the side frames at the blunt ends thereof, a canopy fitted over the side frames, and hooks depending from the lower edge of the side frames for engagement with the side rails of a bed.

In testimony whereof I affix my signature.

LILLIAN C. NESBITT. [L. S.]
